DESIGN FOR A DRILL PRESS GUARD

James Tate, Milwaukee, Wis., assignor to The
Delta Manufacturing Company, Milwaukee,
Wis., a corporation of Wisconsin

Application June 5, 1937, Serial No. 69,692

Term of patent 7 years

To all whom it may concern:

Be it known that I, James Tate, a citizen of the United States, residing at Milwaukee, in the county of Milwaukee and State of Wisconsin, have invented a new, original, and ornamental Design for Drill Press Guards, of which the following is a specification, reference being had to the accompanying drawing, forming part thereof.

In the drawing,

Fig. 1 is a side elevation of a drill press guard showing my new design;

Fig. 2 is a top plan view;

Fig. 3 is a front elevation, and

Fig. 4 is a rear elevation thereof.

I claim:

The ornamental design for a drill press guard, as shown.

JAMES TATE.
